PERCUSSION DRILL FEED MEANS

Victor E. Hastings, Los Angeles, Calif.

Original application April 5, 1943, Serial No. 481,937. Divided and this application February 2, 1945, Serial No. 575,879

3 Claims. (Cl. 255—22)

1

This discovery is in the art of deep well drilling and the concept is, particularly, in hydraulic means for advancing percussion bit means as the hole is bored down.

Churn or percussion drills employ a heavy, elongate shank with one or another kind of cutter on its lower end. The instant invention concerns a churn bit which is reciprocated by immediately adjacent motor means which must be lowered step by step during the drilling operation to follow the leading bit. Whatever the type of this locally placed motor means must be provided whereby it can be at all times under reliable control, first to hold the motor against rotation, and secondly to solidly sustain the motor at all levels of work, and thirdly to gradually lower the motor as the bit deepens the hole.

An object of the invention is to provide a simple, practical, reliable, low weight electric cable conduit and motor carrier hereinafter called the drill pipe, and an object is to provide automatic bit controlled means for advancing the drilling assembly, that is the pipe, the actuating motor, and the cutting bit step by step as the hole is cut deeper.

The instant motor feed or advancing means is shown as used in connection with what is known as a solenoid motor and with means for automatically rotating the bit during its, the bit's, operation. The present feed means not only lowers the motor automatically but also holds the bit turning means against rotation from any cause, as very clearly distinguished from proposed use of cables, as known in the patent art, to suspend and lower bit and motor assemblies.

It is an object of the invention to provide a churn drill assembly and control and lowering means therefor that, consideration being had for the several functions, is of simple and rugged construction, that is economical of power and time, and of manual labor, that eliminates many objections to currently used forms of churn drills, that is not of undue cost of construction, that involves structural features easily repairable or obtainable in nearly all field markets in the industry and are of such weights, in piece elements, as to be readily portable into difficult terrain.

The invention consists in certain advancements in this art, for the purposes set forth and adaptations thereof, as ensuingly disclosed, and having with the above, additional objects and advantages hereinafter developed, and whose constructions, combinations and sub-combinations, and details of means, and the manner of operation will be made manifest in the description of the

2

herewith illustrative embodiment; it being understood that modifications, variations, and adaptations may be resorted to within the scope, spirit, and principle of the invention as it is more directly claimed presently.

Figure 1 is a side elevation of the drill pipe suspending head works; partly axially in section and showing a coaxial, axially broken away, solenoid motor at the foot of the drill pipe. Figure 10 2 is an axial section of the hydraulic, head works valve for advancing the pipe down, and Figure 3 is a mid-length, cross-section of the said valve. Figure 4 is a diagram of the circuit for an electric motor related to the head works, pipe controlling means. Figure 5 is an axial section of the stationary drill pipe to show location of the pipe control switch. Figure 6 is a cross-section on line 6—6, Figure 5, of means for holding the switch stem against rotation in the pipe, and 15 Figure 7 is an axial section of a fragment of the pipe with the cross-head in elevation. Figure 8 is a cross-section on line 8—8, Fig. 5, of the switch device, for down feed of the pipe, operative by the switch stem. Figure 9 is an elevation of 25 a portion of the stem to show the closer plate of the pipe control switch. Figure 10 is an axial section showing the contact blocks of the switch.

A hollow churn bit 2 is rigidly attached in suitable manner to the core 6 of a solenoid motor 10 which is rigidly attached to the lower portion of a substantial or rigid suspending column 11 preferably hollow to form a conduit for an electric cable 48—49 and its sheath 50, as well as for serving water to the hole if desired. Means, 30 not shown, are provided to positively rotate the core and the bit, whilst the motor is held solidly against rotation by the pipe column 11, which is suspended stationarily as will be described.

It will be understood that when the solenoid 40 motor 10 is intermittently excited electrically the core-and-bit device will be pulled up rapidly to a suitable degree in the pipe 11 and as the current is broken the said device, preferably of considerable weight, will freely gravitate to make a cutting stroke; all as set forth in my application Ser. No. 481,937, filed April 5, 1943, and of which this disclosure is a division.

The drilling apparatus involves an electrical, 45 control circuit and an object of the invention is that the circuit may be controlled directly by actions of the solenoid driven core-and-bit device incidental with the advance of the cutting bit by deepening of the hole. Therefore the upper end of the motor core 6, Fig. 5, is attached by a swivel 50 20 to the lower end of a tubular stem 21. While

the bit device is capable of desired rotation, the stem 21 is provided with a rigid cross-head 25, having lugs 26 longitudinally slidable in ways 27 along the pipe bore face; thereby holding the stem from rotation but allowing it to axially reciprocate with the motor core.

It will be seen that the stiff, stationarily suspended tool pipe has no action, axial or rotary, in so far as bit action is concerned but serves the dual function of water conduit to the bit and as a stationary support for the solenoid motor 10 fixed on its lower end, see Fig. 1. As the hole may be drilled to considerable total depth it is desirable to reduce dead weight and parts cost. Therefore the size of the pipe may be reduced at a joint 43 and continued in reduced size to the head works. A packing gland 44 is arranged in the pipe chamber in which the stem 21 works to keep it free from water coming down the upper extension of the pipe 11' and flowing into the hollow stem.

As the drill bit cuts earth formation down in the hole the suspended pipe string must be gradually fed down to lower the bit localized motor and the circuit control means and let the bit continue without interference in its work of drilling. At the head of the hole is a motor controlled means, including a hydraulic jack composed of a valved cylinder and a piston therein, and an automatic, bit controlled switch means is provided to control the jack motor and effect operation of the valve. There is shown fixed in the pipe 11 a stationary contact device 45 having a pair of spaced blocks 46-47 insulated from the pipe and connected to the cable wires 48-49 which lie in the pipe.

Fixed on the stem 21 at a position just above the cross-head 25 is a hub 51 on which is insulatedly fixed a contact shoe 52 which is adapted, as the bit cuts its way down the hole, to ultimately come into engagement with the stationary contact blocks 46-47 arranged, in the assembly of the drill pipe, at the lower end of the stroke of the shoe (for said ultimate engagement) and thereby close the circuit in the wires 48-49. The consequence of this is to energize an electric, rotary motor M which functions, by way of a speed reducing gear 53, to rotate a metering drum valve 54 having twin measuring compartments 54', 55 with respective narrow, elongate slots 56-57 opening in longitudinally off-set relation at opposite peripheral sides of the drum. The drum is rotatively fitted in a shell 58 having a bottom spill port 59 and a top nipple 60 to which is joined a down spout 61 leading from the bottom of a deep cylinder 62. Extending up through and packed in the bottom of the cylinder is a hollow piston rod 63 having at its upper end a fixed piston head 64 packed operatively in the cylinder wall and forming a jack head. The tool pipe part 11' extends into the hollow rod 63 and has a make-up joint 65 forming a part of a centering thimble 66 resting centrally on the piston head and having lead branches 67-68 for the electric cable of wires and for jointing of a wash water pipe 69.

The piston head has suitable means 70 for attachable elevating means as may be required to pull the said head from time to time when working with a long string of tool pipe 11-11'.

For replenishing the cylinder 62 with water at intervals a water supply pipe 71 feeds to the bottom of the cylinder under the piston by way of a manual valve 72, and where possible this water head may be used to raise the piston in

the cylinder and thereby the tool pipe 11. It will be seen that as the normally stationary, suspended, non-rotary pipe 11 is lowered by the jack piston as the valve 54 measures out the water the pipe electric contacts 46-47 break engagement with the switch shoe 52 and the valve motor M will be stopped, as it will also when the stem 21 is retracted by the solenoid motor 10. From time to time additional sections of pipe 11' will be strung in at the head works as depth of hole is gained.

As the core actuated bit 2 gradually cuts down the earth formation in the bottom of the hole the shoe eventually repeatedly closes the motor (M) circuit through the normally stationary, pipe-carried contacts 46-47 with the result that the drum valve is rotated step by step to shift, say, port 57 of the empty chamber 54' from bottom position, Fig. 3, to upper or top position to drain water by way of the nipple 60 from the cylinder 62 to fill the chamber 54' and effect the lowering of the piston 64 one step (measured by the volume of the chamber). It will be seen that as soon as the port 57 begins to take in water the piston 64 and its pipe 11 will start to move down faster than the bit 2 can cut the foot rock and therefore the pipe-carried contacts 46-47 are lowered out of range of the core-carried shoe 52. The consequence is that the drum valve 54 must stop in a position with the port 57 at its top position whilst the port 56 has been turned to its bottom position (reverse to that in Fig. 3) to spill its water load in preparation for taking a new, measured volume at the next period of operation of the motor M. Briefly, the piston 64 is lowered each time a port 56 or 57 is brought to the top position by rotation of the drum valve 54, and the motor M is killed by descent of the piston 64 with its pipe mounted contacts 46-47 to put these contacts well below the instant lowest point in the path of the reciprocating, drill stem shoe 52. Further, the circuit of motor M is closed only when the core actuated bit 2 cuts down far enough to allow the shoe 52 to again start its closely repeated contacts with the contacts 46-47; the drilling motor 10, including its core 6, and the pipe 11, with said contacts all being carried and controlled by the piston 64.

To remove the drill pipe and the drill it is only necessary to hitch on the usual head works elevator and pull up the joint 65 to draw the pipe string out of the piston and break it down joint section by section. If there is enough water pressure in the feed pipe 71 it can be used to elevate the piston to draw the drill pipe when it is to be broken down.

Since air may accumulate under the piston, from valve 54, the air pipe 64' is provided to let off the air from time to time as the cylinder is filled with a fresh supply of water for another controlled descent of the piston.

The measured volume of water taken alternately into the compartments of the valve 54 positively determine the step-by-step descent of the pipe 11; each step being very much more than the length of the stationary contacts 46-47. The motor core 6 continuously reciprocates and ultimately brings the shoe 52 repeatedly into engagement with the contacts 46-47 whereby the circuit of the jack motor M is intermittently completed until the valve 54 makes a new half-revolution and a measured charge of water is tapped from the tank 62 to lower the drill pipe 11 with its foot attached, solenoid motor 10 and

by this action lower the contacts 46-47 well below the instant range of the core carried shoe 52. As the tapped water pours into the uppermost of the valve ports (56 or 57) air from the related compartment ascends into the tank and at the same time the waste load is spilled from the other compartment to the drain 59.

What is claimed is:

1. In a well drilling apparatus: a cylinder and a drilling piston supported and controllable by water in the cylinder, and means for intermittently drawing water from the cylinder to lower the piston step by step during drilling; said means including a valve shell having vertically opposite ports for intake and spill of the water and a horizontal-axis drum valve provided with separate chambers having a pair of peripherally opposite ports repeatedly rotative into concurrent register with the upper and lower shell ports to alternately drain a measured volume of water from the tank and lower the piston a predetermined degree, and means controlled by the piston to rotate the valve and including a drum rotating motor, and a pipe column attached to and lowered by the piston and having a device to break the motor circuit as the piston descends.

2. In a well drilling apparatus: a cylinder and a piston carrying drilling means including a drill guide column, and which piston is controlled by water in the cylinder, and means for intermit-

tently drawing water from the tank to lower the piston step by step; said means including a valve shell having vertically opposite ports for intake and spill of water from the cylinder and a horizontal-axis drum valve having a plurality of measuring chambers which have diagonally opposite ports to be rotated into concurrent register with the shell ports to take in a measured volume of cylinder water in one chamber whilst the other chamber is discharging to the outlet port of the shell, and a motor for rotating the drum valve in successive actions and having a circuit which is controlled by the piston carried column and includes switch contacts fixed on the column.

10 3. The apparatus of claim 1; and including means to replenish the exhausted cylinder below and for elevating the piston, and means for blowing off trapped air in the tank from time to time.

VICTOR E. HASTINGS.
